GUARD FOR PRESSES AND LIKE
MACHINE TOOLS

Eugene Sydney Dumont, Tottenham, London, England, assignor to Benjamin Electric Mfg. Company, Des Plaines, Ill., a corporation of Illinois

Application January 28, 1935, Serial No. 3,884
In Great Britain February 21, 1934

6 Claims. (Cl. 74—613)

My invention relates to improvements in guards for presses and the like, and more particularly to the type of guard arranged to move on horizontal guides in front of the tool in advance of the tool movement at each operation and operated to push out of the path of the tool the operator's hands or arms. In the past such guards have only been made to move transversely across the front of the press opening and it has been found that it is still possible for an operator to insert his arm over the top or sides of such guards and for accidents to occur. Accidents have also been known to occur with such guards through the guard striking an operator's arm on the inner side of the elbow and causing the operator's forearm to be jerked under a descending die of a press. The object of the present invention is to provide a guard which will prevent such occurrences as above mentioned and generally be more effective.

In the drawing, in which one form of my invention is shown,

Figure 1 is a front elevational view showing my improved guard in position with respect to a press;

Fig. 2 is a plan view of the construction of Fig. 1;

Fig. 3 is a section on the line 3—3 of Fig. 1; and

Fig. 4 is a perspective view of the movable guard and associated parts.

Referring to the drawing in detail, the construction shown comprises a bracket 1 secured by means of screws 2 to the press or other machine, a horizontal guide 3 mounted on the bracket 1 and extending across the front of the press 4, a sleeve 5 slidably mounted on the guide 3, caused to move transversely across the front of the press at each stroke of the press by means of an actuating link 6 pivotally secured to the sleeve, a bracket 7 extending upwardly from said sleeve and mounted thereon, a vertical guard member 8 here shown as a spring extending between the upper end of the bracket and the sleeve, upper and lower arms 9 and 10, respectively, extending rearwardly from said bracket, a second guard member 11 swingably mounted on the rearwardly extending arms 9 and 10, a channel guide 12 having a straight portion extending across the front of the press and having a curved side portion 13 extending rearwardly and along the side of the press forming a guide for the swinging end of the swinging guard member 11, and a supporting slide 14 for the bracket 7 secured to the upper rearwardly-extending arm 9.

The guard member 11 comprises a substantially

rectangular frame having two upright members 15 and 16 and two horizontal members 17 and 18 connecting the upright members 15 and 16, as shown in Fig. 4. The upright member 15 constitutes the swingable edge of the guard member 11 and the upright member 16 constitutes the pivotal edge of the guard member 11. The member 16 is pivotally mounted in the arms 9 and 10. The upper end of the upright 15 is guided in the channel guide 12 so that the swingable edge of the guard member travels in a rectangular path across in front of the tool in the first part of its movement and swings to the rear about the axis of the upright 16 in the latter part of its movement.

In operation, should the machine operator fail to withdraw his hands or arms from under the press tool when the tool approaches the end of its travel, the front transverse moving guard 8 will push them to one side and if for any reason the operator, by reason of abnormal reach or by reaching over the guard at an acute angle, can still leave his hands or arms in danger the inner guard 11 during the course of its circumferential movement round the tool will push them out of the danger line.

The swinging guard member 11 is guided in its movement by the engagement of the forward part of the guard 11 in the channel guide 12, the guard moving from the full-line positions shown in Figs. 1 and 2 to the dotted-line positions. As shown in Fig. 2, during the latter part of the movement of the guard 11, the slide 14 disengages the side of the channel guide 12 to enable the guard member 11 to complete its swinging rearward movement.

The aforesaid moving guard members may be used in conjunction with any desired arrangement of fixed guard members disposed on each side of the tool. If desired, I may omit the front transverse moving guard and rely merely on the combined transverse and circumferential moving member only.

Further modifications will be apparent to those skilled in the art and it is desired, therefore, that the invention be limited only by the prior art and the scope of the appended claims.

Having thus described my invention, what I claim and desire to secure by Letters Patent is:

1. A safety device for presses and the like comprising movable guard means and movement controlling means controlled in synchronism with the press operation for causing said guard means to move across in front of the tool in the first part of its movement and from front to rear at the side of the tool in the latter part of its movement.

2. A safety device for presses and the like comprising movable guard means and movement-controlling means controlled in synchronism with the press operation for causing said guard means to move across in front of the tool in the first part of its movement and from front to rear at the side of the tool in the latter part of its movement, said movement-controlling means comprising guide means for the swingable edge of said guard 5 having a rectilinear portion extending across in front of the tool and a curvilinear portion extending rearwardly from said rectilinear portion.
3. A safety device for presses and the like comprising a rectilinear guide extending transversely 10 with respect to the press, a slide mounted on said guide, a guard pivotally mounted on said slide to swing about a substantially vertical axis, and means for causing the swingable edge of said guard to travel in a substantially rectilinear path 15 across in front of the tool in the first part of its movement and to swing to the rear about its axis in the latter part of its movement.
4. A safety device for presses and the like comprising a rectilinear guide extending transversely 20 with respect to the press, a slide mounted on said guide, a guard pivotally mounted on said slide to swing about a substantially vertical axis, and means for causing the swingable edge of said guard to travel in a substantially rectilinear path 25 across in front of the tool in the first part of its movement and to swing to the rear about its axis in the latter part of its movement comprising guide means for the swingable edge of said guard having a rectilinear portion extending across in front of the tool and a curvilinear portion extending rearwardly from said rectilinear portion.

tending rearwardly from said rectilinear portion.

5. A safety device for presses and the like comprising a rectilinear guide extending transversely with respect to the press, a slide mounted on said guide, a guard member carried by said slide and extending upwardly therefrom, arms extending rearwardly from said guard member, a second guard member pivotally mounted on said rearwardly extending arms to swing about a substantially vertical axis, and means for causing the 10 edge of said pivotally mounted guard member to travel in a rectilinear path across in front of the tool in the first part of its movement and to swing to the rear about its axis in the latter part of its movement.

6. A safety device for presses and the like comprising a rectilinear guide extending transversely with respect to the press, a slide mounted on said guide, a guard member carried by said slide and extending upwardly therefrom, arms extending rearwardly from said guard member, a second guard member pivotally mounted on said rearwardly extending arms to swing about a substantially vertical axis, and means for causing the 20 edge of said pivotally mounted guard member to travel in a rectilinear path across in front of the tool in the first part of its movement and to swing to the rear about its axis in the latter part of its movement, said movement-controlling means comprising guide means for the swingable 25 edge of said guard having a rectilinear portion extending across in front of the tool and a curvilinear portion extending rearwardly from said rectilinear portion.
